SYNCHRONIZING SIGNAL GENERATION SYSTEM

Kurt Schlesinger, Berlin, Germany, assignor, by
mesne assignments, to Loewe Radio, Inc., a cor-
poration of New York

Application November 10, 1936, Serial No. 110,042
In Germany November 18, 1935

2 Claims. (Cl. 178—7.2)

In the case of television scanning devices, which operate by the scanning of a multi-cell photo-electric screen by means of a cathode ray, there has been employed heretofore, according to publications which have become known, a mechanical device, usually a light siren, for producing the correct deflection frequencies, and synchronization signals have been produced by the same means. A method of this kind does not produce the synchronous signals as a matter of course only when the scanning ray has reached the edge of the photo-electric screen, but the initiation of the synchronization signal depends on the particular oscillation conditions of the siren, which is coupled more or less loosely with the movement of the ray. It is known that in the case of electrically generated synchronization signals of this nature curvatures of the image co-ordinates very frequently occur. Even a hum- ming component in the mains-connected apparatus may give rise to deviations from the straight line as regards the edges of the image.

Curvatures of this kind in the co-ordinates may be fundamentally obviated in an arrangement operating with scanning disc when the scanning image point itself causes the synchronization signal, viz., when it reaches a prescribed edge of the image. It is then immaterial whether the scanning point arrives at the edge of the image with small errors in time—too early or too late. The synchronization signal is always initiated in such fashion that the reversing points of the synchronized received-image point are all situated on a completely straight marginal line, which in these cases is the transmitted television image of the straight edge of the transmission screen. Errors in the movement of the image point are accordingly eliminated automatically in the method of the self-synchronizing scanning point. This method may be referred to generally as "auto-synchronization."

The present invention sets forth auto-synchronization methods in the case of the ikonoscope.

The invention relates to a transmission whereby the synchronizing signals have an amplitude different from that of the image contents signals. There is assumed to exist in an ikonoscope system an intercepting plate 1, which in the known fashion is made up of a cell mosaic. The plate is scanned in lines by a cathode ray 2, which proceeds from an electron-optical system 3/4 and projects on to the plate a sufficiently sharp scanning point.

The method which solves the problem of syn-

chronization of the ikonoscope without mechanically moved devices is illustrated in the drawing. This consists in the use of an amplitude filtering method as applied to the deflecting potentials. There are shown behind the anode 3 of the ray-generating system the first deflecting plates 10. They are connected with a relaxation generator 11, which is preferably applied to the plates in push-pull. An amplitude filter consisting of a simple two-electrode valve 12 is connected by its anode to that particular plate 10 which upon the deflection of the ray conducts positive potentials to the synchronizing edge. The potential of a biasing battery 13 is selected to be somewhat lower than the maximum potential value at the deflecting plate 10. In consequence, after the potential value 13 has been exceeded, the amplitude filter 12 is traversed by an impulse which, in the manner known per se, may be tapped by the transformer 14 and additionally utilized.

Since the deflecting potential is closely associated with the geometrical position of the scanning ray 2 on the mosaic plate 1, there may be obtained also in this purely electrical fashion the occurrence of synchronization impulses corresponding with a straight edge of the image and adjusting the same at the receiver, even if the deflecting generator 11 is affected by interfering modulations.

The inclusion of a potentiometer between the relaxation generator and the amplitude filter, which may be purely galvanic or may also contain a condenser, may naturally be made use of with the advantage that the counter-battery 13 requires to have a lower voltage. A lower limit in respect of the distribution of the potential is provided by the insecurity limit of the amplitude filter 12 (starting current range=a few volts).

According to the invention, the synchronization impulses from the transformer 14 may be utilized for suppressing the aerial current or, as shown in the drawing, they may also be added in direct fashion in the correct polarity to the main amplifier connected with the signal plate 5, which represents a simplification in the electrical apparatus by the omission of special synchronization amplifiers. The transformer 14 is preferably tuned to the duration of the impulses, and if necessary, for the purpose of eliminating the oscillatory counter-impulse of the induction, must act on the amplifier 6 by way of a rectifier 15.

In all of these synchronization methods, which make use of the cathode ray itself or its deflecting potentials for obtaining the synchronization sig-

nals, the possibility is provided of employing as control frequency for the line frequency one of the known stationary frequency standards, for example quartz, magnetostrictive rods and the like. The receiver follows in positive fashion the given number of lines of the transmitter, and the use of rotating sirens may be dispensed with.

I claim:

1. In a television transmitting system, a cathode ray tube, means for developing a cathode ray beam in said tube, means for deflecting said beam, target means for developing electrical signals in response to the action of the cathode ray beam thereon, output means for said target means, means for generating an electrical wave form for energizing said deflecting means with a substantially sawtooth shaped wave form, a first unidirectional conducting means, means for impressing at least a portion of the latter generated wave form onto said unidirectional conducting means, means for maintaining said first unidirectional conducting means at a predetermined threshold response state, a first inductive means connected with said first unidirectional conducting means and having at least a portion of the current passing through said first unidirectional conducting means impressed thereon, a second inductive means coupled with said first inductive means, a second unidirectional conductor electrically connected to said second inductive means for rectifying the current passing through said second unidirectional conductor, and means for mixing the signals passing through said second inductive means and said second rectifier with the signals occurring in the target output circuit.

2. A system as claimed in claim 1 wherein said means to deflect the cathode ray beam comprises a pair of electrostatic plates and wherein the energy supplied to the first unidirectional conductor comprises a portion of the energy impressed upon one of said electrostatic plates. 20
